TYPEWRITER CASE

Alexander C. H. Weiss, Deerfield Beach, Fla., assignor to the United States of America as represented by the Secretary of the Army

Application January 23, 1958, Serial No. 49,378

Term of patent 14 years

(Cl. D87—5)

The invention described herein, may be manufactured and used by or for the Government for governmental purposes, without the payment of any royalty thereon.

I claim:

The ornamental design for a typewriter case, substantially as shown.
